CONTROL APPARATUS FOR ENGINE
STARTERS

John B. Dyer, Pendleton, and James L. Arthur, Anderson, Ind., assignors, by mesne assignments, to General Motors Corporation, Detroit, Mich., a corporation of Delaware *

Application August 12, 1933, Serial No. 684,807

14 Claims. (Cl. 290—38)

This invention relates to control apparatus for engine starting devices, particularly that type of engine starting device which includes an electric starting motor which is rendered operative by 5 operation of some control member which performs some other function than the mere control of the starting motor, is rendered inoperative during the time the engine is running under its own power and is adapted to be restarted in the event 10 of accidental stalling of the engine either automatically or by operation of the aforesaid control member.

Devices of this character have been previously constructed in which the starting motor is arranged to be rendered operative by the operation of the ignition switch alone or by the operation of such switch and some other control member such as the accelerator pedal or the clutch pedal. In such devices the suction of the engine has been utilized to prevent operation of the starting motor during the time that the engine is running under its own power and certain difficulties have been encountered in providing a suction operated control device which is sufficiently sensitive to prevent 20 operation of the starting motor when the engine is running under heavy load with wide open throttle, at which time the suction is of course very low, and at the same time will not be operated by the engine suction during the cranking of the engine by the starting motor under which conditions the suction may approach that which exists when the engine is operating under heavy load at wide open throttle.

It is the primary object of this invention to 25 provide control apparatus for starting devices of this character which is rendered inoperative by the engine suction during all operating conditions when the engine is running under its own power but which are so constructed that the starting motor is never rendered inoperative during the cranking operation.

It is a further object of the invention to provide 30 means operated by engine suction to control the starting device in the manner aforesaid and also to provide means controlled by the generator to render the starting motor inoperative during the operation of the engine under its own power so as to provide a further means of attaining this result in case the suction operated means becomes defective or fails to operate.

These objects are accomplished according to 35 the present invention by the provision of a suction operated switch which controls the operation of the starting motor and which is provided with contacts which are opened and closed by

the action of a suction operated diaphragm, the latter being subject to two suctions on its opposite sides, one of these suctions being communicated to one side of the diaphragm from a point posterior to the carburetor throttle, while suction is communicated to the opposite side of the diaphragm from a point anterior to the throttle. With such a device when the choke valve is closed, or nearly closed, as is the custom when starting the engine, these suctions tend to balance each other and a spring normally holds the diaphragm in such position as to maintain the suction operated switch in closed position during the engine cranking. When, however, the engine is operating under heavy load with wide open throttle, the choke valve is also open so that little, if any, suction is communicated to one side of the diaphragm while to the other side of the diaphragm there is sufficient suction communicated to move the diaphragm against the pressure of the spring and so cause the switch to be opened under any operating conditions when the engine is running under its own power.

Further objects and advantages of the present invention will be apparent from the following description, reference being had to the accompanying drawings wherein a preferred embodiment of one form of the present invention is clearly shown.

In the drawings:

Fig. 1 is a wiring diagram of one form of the present invention.

Figs. 2 and 3 are wiring diagrams of modified forms of the invention employing a somewhat different type of control mechanism.

Fig. 4 is an enlarged detail view of the carburetor and the suction operated switch.

Referring to Fig. 1 of the drawings, the starting motor is indicated at 20 and has an armature shaft 22 on which is splined a sleeve 24 which is secured to one member of an overrunning clutch 26, the other member of which is secured to or integral with a driving pinion 28 adapted to be moved into engagement with a gear 30 formed on the engine flywheel in order to turn said gear and start the engine whenever the starting motor 20 is operative. The sleeve 24 is moved to the right in Fig. 1 in order to effect engagement of the pinion 28 with the flywheel gear 30 and when this takes place the circuit between the starting motor 20 and the battery is closed by means 32 which will now be described in order to cause the starting motor to become operative.

To this end the sleeve 24 is provided with a grooved collar 32 which is slidable on the sleeve and said collar is engaged by pins 34 which pro-

55

ject from the lower ends of a bifurcated lever 36 suitably pivoted at 38 and pivotally connected at its upper end with the armature 40 of a solenoid which is indicated in its entirety by the reference 5 character 42. When the solenoid 42 is energized the lever 36 is moved in a counterclockwise direction and through the medium of the collar 32, compresses a spring 44 which surrounds the sleeve 24 between the collar and the clutch 26 10 so as to move the pinion 28 into engagement with the flywheel gear in the usual manner and at the same time the left end of the armature 40 operates the movable contact 46 of the main starting motor switch to close the starting motor 15 switch.

The starting motor is grounded through the connection 48 while a wire 50 leads from said motor to a fixed contact 52 of the starting motor switch, while a second fixed contact 54 is connected by a wire 56 with a wire 58 which leads from the generator 59 hereinafter described, to a battery 60 grounded through the connection 62. The movable contact 46 is normally held out of engagement with contacts 52 and 54 by a 20 compression spring 64, but upon energization of the solenoid, the movable contact is moved into engagement with said fixed contacts to close the circuit of the starting motor. When this takes place current will flow from the battery 60 to the 25 ground through the connection 62, through wires 58 and 56, contacts 54, 46, 52 and the wire 50 to the starting motor and thence through connection 48 to ground.

The starting motor will then cause the engine 30 to start and when the engine is running under its own power, the starting motor is rendered inoperative by means afterwards described, at which time the lever 36 and the parts operated thereby will be moved to the normal position 35 shown in Fig. 1 with the pinion 28 out of engagement with the gear 30.

The operation of the solenoid 42 is both manually and automatically controlled, the solenoid being caused to become energized upon the operation of one or more manually operated switches 40 (in the form shown in the drawings by operation of the ignition switch only), and is de-energized by the action of engine suction. As stated previously, this suction is insufficient to cause de- 45 energization of the solenoid during the time the engine is being turned by the starting motor, but becomes sufficient to effect this function when the engine starts to operate under its own power 50 and the suction operated control device is so constructed that the energization of the solenoid will be prevented as long as the engine continues to so operate, no matter what the operating conditions 55 may be.

In order to control the operation of the solenoid in this manner it is provided with a winding 66, one end of which is connected by wire 68 with a fixed contact 70 of the ignition switch which is provided with a movable contact 72 60 connected by the wire 74 with the wire 58 above referred to, which leads to the battery. The fixed contact 70 is connected by a wire 75 which leads to the ignition system of the engine which is not shown herein. The other end of the winding 66 65 is connected by a wire 76 with a binding post 78 connected to the fixed contact 80 of a suction operated switch indicated in its entirety by the numeral 82. The switch has a movable contact 84 70 grounded as indicated at 86.

Obviously when the ignition switch is closed 75

and the contacts 80 and 84 are closed, current will flow from the battery to ground through the connection 62 and from the battery through wires 58 and 74, the ignition switch and the wire 68 to the winding 66, thence through the wire 76, contacts 78 and 80 to ground again so that whenever the ignition switch and the switch 82 are both closed, the solenoid will be energized to cause the starting motor to become operative and to cause engagement of the gear 28 with the flywheel 30 as previously described. The ignition switch always remains closed during the entire operation of the engine, but the switch 82 although normally closed, when the engine is not in operation, is caused to be opened when the engine is running as previously described and the operation of said switch 82 is entirely automatic as will appear hereinafter.

The reference 88 denotes the intake manifold of the engine which is of the usual construction 20 and to which is connected a carburetor 90 which is provided with the usual fuel chamber 92 and intake passage 94 to which air is admitted through the open end 96 and to which fuel is supplied through the main nozzle 98 and a passage 100 which supplies fuel for idling. The flow through the intake passage is controlled by a throttle valve 102 which is of conventional construction and is adapted to be opened or closed 25 to varying degrees to control the speed of the engine in the usual way. A choke valve 104 is also provided adjacent the inlet end of the intake passage. This valve is designed to be opened wide during normal operation of the engine and its use is primarily to facilitate starting of the engine, at which time the said valve 104 is almost or entirely closed. The carburetor may be of any conventional design.

The switch 82 comprises two metal shells 110 and 112 which are flanged at the edges and are suitably connected together to form a fluid tight joint with a flexible diaphragm 114 clamped between the edges of the shells. This diaphragm may be of any suitable flexible material and two 40 metallic disks 116 and 118 of concave form are provided on opposite sides of the diaphragm while extending through the diaphragm and these disks 45 is a rivet which is provided with an enlarged head 120 adapted to engage a flat spring 122 which carries the movable contact 84 and is suitably riveted to the housing 110, the rivet 120 being riveted over the disk 118 to hold the assembly together.

Extending through the shell 112 is a nipple 124 which is flanged within the shell and is provided with a shoulder 126 which engages a washer 128 lying between the shoulder and the shell, while the end of the nipple which projects outside the shell is threaded and a suitable nut 130 may be tightened against the shell to provide a fluid tight 50 shell, the shell being clamped between the washer 128 and the nut. Also threaded on the nipple is a coupling member 132 which has a reduced threaded end 134 adapted to be screwed into the wall of the manifold 88 and having a bore 136 55 therethrough which communicates with the manifold and permits the suction of the manifold to be communicated therethrough to the space within the shell 112 so that the suction thus communicated tends to pull the diaphragm 114 to the right 60 to the position shown in Fig. 4 of the drawings. Received within the nipple 124 is a spring 138 which normally moves the diaphragm to the left 65 so as to hold the contacts 80 and 84 in engagement when the engine is not running. This spring 70

is received between the disk 118 and a disk 140 which is positioned between the end of the nipple 124 and a shoulder on the coupling member 132. Such disk is provided with a small orifice 142 the purpose of which will be described later.

Communicating with the space on the opposite side of the disk 114 is a suction conduit 144, which is provided with suitable coupling members 146 and 148, by means of which the conduit is connected to the shell 110 and to the carburetor intake passage at a point immediately posterior to the choke valve. Obviously, whatever suction or partial vacuum is maintained at any time at the point where the coupling member communicates with the carburetor intake will be communicated to the space within the shell 110 on the left side of the diaphragm as viewed in Fig. 4.

The operation of this switch is relatively simple. When the engine is at rest the spring 138 holds the switch contacts 80 and 84 closed. Normally when starting, the choke valve is closed or partially closed, while the throttle is open to some extent. Obviously when the choke valve is closed or partially closed there would be a suction or partial vacuum maintained at the point where the suction conduit 144 communicates with the carburetor intake and this suction will be communicated to the space within the shell 110 tending to aid the action of the spring 138 in holding the switch closed. At this time suction will be communicated also through the passage 136 to the right side of the diaphragm 114, but such suction will not be sufficient during the time the starting motor is cranking the engine to cause the switch to open. However, when the engine begins to run under its own power the choke valve is necessarily opened to some extent, reducing the suction on the left side of the diaphragm and the construction is such that just as soon as the engine is self-operative the suction communicated to the right side of the diaphragm becomes sufficient to overcome both the pressure of the spring 138 and the suction communicated to the left side of the diaphragm and causes the switch to open. Under all operating conditions the choke valve 134 must be opened to such an extent that it will be impossible to create sufficient suction on the left side of the diaphragm to cause the switch contacts 80 and 84 to be held in engagement, but during the cranking operation when the choke valve is closed, the suction communicated to the left side of the diaphragm will always be sufficient to hold it closed and prevent its opening by the suction communicated through the passage 136.

It will be apparent, therefore, that the effective suction tending to move the diaphragm to the right to open the switch is always insufficient during the cranking operation to effect this function, but is never insufficient during the operation of the engine under its own power to fail to effect such function.

The orifice 142 is provided for the purpose of delaying the return of the diaphragm to the left after the switch has been opened. This is provided primarily for the purpose of preventing the reclosing of the switch, in the event that the engine has been started but stops practically immediately thereafter, before the shaft of the starting motor has ceased to turn. If some means of this nature were not provided the starting motor might be rendered operative and the gear 28 moved into engagement with the flywheel while it was still spinning, under the conditions referred to, which might result in broken teeth on the gear of flywheel, or other damage.

In the modified form of the invention shown in Fig. 2, the suction operated switch which has been previously described, is of exactly the same construction as in the form of the invention shown in Fig. 1 and the description thereof need not be repeated. However, the means for closing the switch of the starting motor and causing the engagement of the pinion driven thereby with the engine flywheel gear is somewhat different in construction and instead of employing an electromagnet or solenoid for this purpose, applicant has employed a small auxiliary electric motor, the construction being the same as that shown in applicant's copending applications Nos. 589,642 and 608,476. In this construction as shown in Fig. 2, the starting motor is indicated at 160 and has an armature shaft 162 on which is splined a sleeve 164 which is secured to one member of an overrunning clutch 166, the other member of which is secured to or integral with the driving pinion 168, which is adapted to engage the flywheel gear 170 previously described. The sleeve is provided with an external spiral thread 172 on which is threaded a beveled gear 174 which engages a beveled gear 176 secured to the armature shaft 178 of a relatively small auxiliary motor 180 of the shunt wound type. The gear 174 is prevented from movement axially with respect to the shaft 22 as fully described in the copending application No. 589,642 and since movement of the gear in this manner is prevented, rotation of said gear by the motor 180 causes longitudinal movement of the sleeve 164 which first causes engagement of the pinion 168 with the gear 170 and, subsequently, the closing of the switch of the starting motor. For this purpose there is secured to the sleeve in any suitable manner a grooved collar 182 which engages pins 184 projecting from the bifurcated end of a lever 186 pivoted at 188 and having pivotally connected to the lower end thereof a rod 190 carrying a movable contact 192 which is adapted to be moved into engagement with fixed contacts 194 and 196 of the starter switch. The contact 194 is connected by a wire 198 with the starting motor 180 which is grounded by the connection 200 while the contact 196 is connected by a wire 202 with a wire 204 similar to the wire 58 previously referred to and leading to the battery 206 grounded at 208. Wire 204 is connected by a wire 210 with the generator 211 in the usual way.

When the starter switch is closed, current will flow to ground through the connection 208 and from the battery through wires 204, 202, the starter switch and wire 198 to the starting motor 180 and from thence to ground through the connection 209. The operation of the auxiliary motor which brings about the functions previously described, is controlled by operation of the ignition switch and a suction operated switch 213 of exactly the same construction as that described hereinbefore. For this purpose the motor 180 which is provided with a shunt field 212 is connected by a wire 214 with the fixed contact 216 of the ignition switch which is also connected with the wire 217 leading to the ignition system of the engine and is adapted to be engaged by a movable contact 218 connected by the wire 220 with the wire 204. Connecting with the auxiliary motor 180 is also a wire 222 leading to the binding post 224 which is similar to the binding post 78 and a ground connection 226 similar to the ground connection 86 connects the suction operated switch with the ground.

When the ignition switch is closed current will

flow from the battery to ground through the wire 208 and from the battery through wires 204, 220, the ignition switch, wire 212 to the auxiliary motor, thence through wire 222 to the suction operated switch 213 and through the ground connection 226 to ground again when the suction operated switch is closed. The completion of this circuit, causes the operation of the auxiliary motor 180 and rotation of the gear 174 to cause engagement of the pinion 168 with gear 170 and the closing of the starting motor switch. The starting motor then cranks the engine and when the latter becomes operative the suction operated switch is opened in the manner hereinbefore referred to and the operation of the auxiliary motor ceases. When this takes place the sleeve 164 is moved to the left in a manner described in greater detail in the pending applications above referred to, which disengages the driving pinion 20 from the flywheel gear and opens the starter switch. As previously pointed out, the construction of the auxiliary motor and starting motor is the same as that described in the earlier applications and a construction of the suction operated control switch in this form of the invention is exactly the same as in the form first described.

In the form of the invention shown in Fig. 3, the construction is precisely the same as shown in Fig. 2, with one exception. Only this particular exception will be described in detail hereinafter and the several parts of the two forms of the invention which are the same are indicated on the drawings by the same reference numerals. The difference in construction previously referred to resides in the provision of a wire indicated by the reference character 230 which connects with the wire 210 between the generator and the usual cut-out relay 232 and at its opposite end is connected with the wire 222 leading from the auxiliary motor to the binding post 224. When the engine begins to run under its own power the generator, through the wire 230, sets up a counter-voltage in the auxiliary motor which causes such motor to become inoperative and in the event of the suction operated control switch becoming defective through wear or for any other reason failing to act, the generator through the medium of the connection described will cause the auxiliary motor to become inoperative when the engine is running under its own power and the generator operating at a predetermined speed.

While the form of embodiment of the present invention as herein disclosed, constitutes a preferred form, it is to be understood that other forms might be adopted, all coming within the scope of the claims which follow.

What is claimed is as follows:

1. Control apparatus for engine starters comprising, a current source, a starting motor adapted to be operated by current from said source, automatic means for controlling a circuit between said current source and the starting motor, an intake conduit for delivering a combustible mixture of fuel and air to the engine, a throttle valve for controlling the flow through said intake conduit and a single means controlled by the suction in said conduit on opposite sides of said throttle valve for controlling the operation of said automatic means.

2. Control apparatus for engine starters comprising, a current source, a starting motor adapted to be operated by current from said source, automatic means for controlling a circuit between said current source and the starting motor,

an intake conduit for delivering a combustible mixture of fuel and air to the engine, a throttle valve for controlling the flow through said intake conduit, a choke valve for controlling admission of air to said intake conduit, suction operated means for controlling the operation of said automatic means, said suction operated means being subject to the suction at two points on opposite sides of the throttle valve but on the same side of the choke valve. 10

3. Control apparatus for engine starters comprising, a current source, a starting motor adapted to be operated by current from said source, automatic means for controlling a circuit between said current source and the starting motor, an intake conduit for delivering a combustible mixture of fuel and air to the engine, a throttle valve for controlling the flow through said intake conduit, a choke valve for controlling admission of air to said intake conduit, suction operated means for controlling the operation of said automatic means, said suction operated means being subject to the suction at two points on the anterior and posterior sides of the throttle valve, but both of said points being posterior to the choke valve. 25

4. Control apparatus for engine starters comprising, a current source, a starting motor adapted to be operated by current from said source, a switch for controlling a circuit between the current source and starting motor, an electro-magnet for operating said switch, a single suction operated means for deenergizing the magnet to cause said switch to open, said suction operated means being subject to different degrees of engine suction simultaneously. 35

5. Control apparatus for engine starters comprising, a current source, a starting motor adapted to be operated by current from said source, a switch for controlling a circuit between the current source and starting motor, an electro-magnet 40 for operating said switch, a single suction operated means for deenergizing the magnet to cause said switch to open, an intake conduit for delivering a combustible mixture of fuel and air to the engine, a throttle in said conduit for controlling the flow therethrough, and means whereby said suction operated means is controlled by the suction on opposite sides of said throttle valve. 45

6. Control apparatus for engine starters comprising, a current source, a starting motor adapted to be operated by current from said source, a switch for controlling a circuit between the current source and starting motor, an electro-magnet for operating said switch, a suction operated means for deenergizing the magnet to cause said 55 switch to open, an intake conduit for delivering a combustible mixture of fuel and air to the engine, a throttle in said conduit for controlling the flow therethrough, a choke valve for controlling admission of air to said intake conduit, and means whereby said suction operated means is controlled by suction at two points in said intake conduit, said two points lying on opposite sides of the throttle valve but on the same side of the choke valve. 60

7. Control apparatus for engine starters comprising, a current source, a starting motor adapted to be operated by current from said source, a switch for controlling a circuit between the current source and starting motor, an electro-magnet for operating said switch, a suction operated switch in circuit with a winding of said magnet to control the operation thereof, and means whereby said last named switch is controlled by 70 75

the suction at two points in said intake conduit on opposite sides of said throttle valve.

8. Control apparatus for engine starters comprising, a current source, a starting motor adapted to be operated by current from said source, a switch for controlling a circuit between the current source and starting motor, an electro-magnet for operating said switch, a suction operated switch in circuit with a winding of said magnet to control the operation thereof, said suction operated switch comprising a fluid tight chamber having a diaphragm movable therein to open and close said switch, and means for communicating the suction maintained in the intake conduit on opposite sides of the throttle valve to said chamber on opposite sides of the diaphragm.

9. Control apparatus for engine starters comprising, a current source, a starting motor adapted to be operated by current from said source, a switch for controlling a circuit between the current source and starting motor, an electro-magnet for operating said switch, a suction operated switch in circuit with a winding of said magnet to control the operation thereof, said suction operated switch comprising a fluid tight chamber having a diaphragm movable therein to open and close said switch, and a plurality of suction conduits for communicating the suction of the intake conduit to said chamber, one of said suction conduits extending from a point above the throttle to one side of the diaphragm and another of said conduits from a point below the throttle to the opposite sides of said diaphragm.

10. Control apparatus for internal combustion engines, comprising in combination, a current source, a starting motor adapted to be operated by current from said source, a switch for controlling a circuit between the current source and starting motor, an electro-magnet for operating the switch, a member for controlling the operation of the engine, means whereby operation of said engine control member causes operation of the magnet to close the starter switch, single suction operated means for deenergizing the magnet to effect opening of the starter switch, an intake conduit for delivering a combustible mixture of fuel and air to the engine, a throttle in said conduit for regulating the flow therethrough, and means whereby said suction operated means is controlled by suction on opposite sides of said throttle.

11. Control apparatus for internal combustion engines, comprising in combination, a current source, a starting motor adapted to be operated by current from said source, a switch for controlling a circuit between the current source and starting motor, an electro-magnet for operating the switch, a member for controlling operation of the engine, a switch operable by said engine control member for closing a magnet circuit to cause the magnet to close said starter switch, sin-

gle suction operated means for breaking the magnet circuit to effect opening of the starter switch, an intake conduit for delivering a combustible mixture of fuel and air to the engine, a throttle in said conduit, and means whereby said suction operated means is controlled by suction on opposite sides of the throttle.

12. Control apparatus for internal combustion engines, comprising in combination, a current source, a starting motor adapted to be operated by current from said source, a switch for controlling a circuit between the current source and starting motor, an electro-magnet for operating the switch, a member for controlling operation of the engine, a switch operable by said engine control member for closing a magnet circuit to cause the magnet to close said starter switch, a normally closed suction operated switch for controlling the magnet circuit and adapted when open to break the magnet circuit to effect opening of the starter switch, an intake conduit for delivering a combustible mixture of fuel and air to the engine, a throttle therein, and means whereby operation of said suction operated switch is controlled by suction on opposite sides of said throttle.

13. Control apparatus for engine starters comprising, a current source, a starting motor adapted to be operated by current from said source, a switch for controlling a circuit between the current source and starting motor, an electro-magnet for operating said switch, an ignition switch, means whereby closing of the ignition switch closes a magnet circuit to effect closing of the starter switch, a single suction operated means operable to break the magnet circuit to effect opening of the starter switch, an intake conduit for supplying fuel mixture to the engine, a throttle therein, and means for communicating the suction of the intake conduit on opposite sides of the throttle to said suction operated means.

14. Control apparatus for engine starters comprising, a current source, a starting motor adapted to be operated by current from said source, a switch for controlling a circuit between the current source and starting motor, an electro-magnet for operating said switch, an ignition switch, means whereby closing of the ignition switch closes the magnet circuit to effect closing of the starter switch, a normally closed suction operated switch adapted when open to break the magnet circuit to effect opening of the starter switch, an intake conduit for supplying fuel mixture to the engine, a throttle therein, and means for communicating the suction of the intake conduit on opposite sides of the throttle to said suction operated switch to open said switch when the engine is running under its own power.

JOHN B. DYER. 60
JAMES L. ARTHUR.
